UNITED STATES PATENT OFFICE.

WILFRID HEUSSER, OF SALT LAKE CITY, UTAH.

BASE FOR ASSAY-BALANCES AND THE LIKE.

1,104,891.

Specification of Letters Patent. Patented July 28, 1914.

Application filed December 20, 1913. Serial No. 302,048.

To all whom it may concern:

Be it known that I, WILFRID HEUSSER, a citizen of the Republic of Switzerland, residing at Salt Lake City, in the county of 5 Salt Lake and State of Utah, have invented certain new and useful Improvements in Bases for Assay-Balances and the like, of which the following is a specification.

My invention relates to base plates for 10 balances and like instruments, and has for its object to provide a base or bottom for balances upon which the protecting case and the balance may be rigidly and accurately secured.

15 A further object is to provide a base that will not be affected by climatic conditions and expand, contract or warp to such an extent as to affect the perfect working of the different parts or the accuracy of the instrument.

20 These objects I accomplish with the device illustrated in the accompanying drawings in which similar letters of reference indicate like parts throughout the several 25 figures and as described in the specification forming a part of this application and pointed out in the appended claims.

In the drawings in which I have shown 30 a substantial embodiment of my invention, Figure 1 is a view in perspective of the device, parts cut away, showing the upper and front sides, with portions of the protecting case. Fig. 2 is a view in perspective of the under and rear sides of the device. 35 Fig. 3 is a vertical section on line α α of Fig. 1. Fig. 4 is a vertical section on line y y of Fig. 3. Fig. 5 is a longitudinal vertical section. Fig. 6 is a transverse vertical section.

40 Prior to my invention and use of a rigid metal base or bottom member for assayers' balances and other scientific balances, the case within which the balances were housed, and the mechanical parts of the balance 45 were mounted on a wooden base or one partially constructed of wood, and provided with a slab, of dark colored glass or similar substance, as a covering for the base and frame work, forming the bottom. When the 50 base or frame work was subjected to the usual climatic changes that occur through moisture, expansion and contraction, the mechanical parts of the instrument were

frequently affected and the glass or other covering broken to such an extent as to 55 render the instrument worthless for the accurate and delicate work required.

I have invented and shown in the drawings herewith a metal base of one part, constructed and braced to prevent warping and 60 undue expansion or contraction, on which the mechanical parts of the instrument are mounted and to which a protecting case for 65 said parts is secured. In said drawings the metal base is shown at A, and consists of a rectangular frame 1, with depending internally threaded bosses 2 at each corner thereof. Said frame 1 has the central portion depressed or cut out to form a downward extended glass receiving and retaining recess 3, within which a dark colored 70 glass or porcelain plate 4 is fastened with a cushioning support 5 thereunder of plaster of Paris or similar substances. The under side of said base A has portions thereof cut 75 out to lighten the weight of said frame 1, and to form transverse or end braces 6, and a longitudinal rear brace 7. Transverse drawer guides 8 are fastened on the bottom of said base A within which guides the 80 drawers 9 are operated. Said drawers are for holding the balance weights and for the general convenience of the assayer or chemist. Within said bosses 2 are inserted the externally and internally threaded sleeve 85 nuts 10 within which the adjusting or leveling screws 11 are operated. An opening 12 is cut in said plate 4 through which is inserted the standard that supports or carries the mechanical parts of the instrument. 90 Said standard is rigidly secured to or in the bottom of said base A. It is to be understood, that while I have shown and described a rectangularly shaped base A, the invention is not to be confined to such forms 95 alone, as any other shape that is desired may be used, also that other slight changes may be made within the scope of the claims, without departing from the spirit of the invention or sacrificing any of its principles. 100

From the above description it will be obvious that I have invented a novel and useful base for such instruments which will not be affected by climatic conditions or any uneven surface upon which the instrument 105 is placed and leveled.

I therefore desire to secure by Letters Patent and claim:—

1. In a device of the class described the combination with the case in which assay balances are housed of a metal base having a downwardly extended recess therein; depending bosses on the corners of said base; leveling screws operable in said bosses; and a plate cushioned in said recess having an opening through one side portion thereof within which an assay balance is mounted.
2. In a device of the class described the combination with an assay balance and housing therefor, of a metal base having a downwardly and three upwardly extended recesses formed therein; depending internally threaded bosses on the corners of said base; leveling screws operable in said bosses; and a glass plate cushioned in said downwardly extended recess having an opening

therethrough within which the balances are mounted.

3. A base for delicately poised instruments consisting of a metal frame having a depression formed in the upper side; internally threaded depending bosses on the corners of said frame; leveling means operable in said bosses; and a glass plate cushioned in said depression on a plane with the upper side of said frame and provided with an opening therein through which the balance is inserted when secured to said metal frame.

In testimony whereof I have affixed my signature in presence of two witnesses.

WILFRID HEUSSER.

Witnesses:

BEN L. CORUM,
W. R. WILLIAMS.
